UNITED STATES PATENT OFFICE.

CHARLES F. KETTERING, OF DAYTON, OHIO, ASSIGNOR, BY MESNE ASSIGNMENTS, TO
GENERAL MOTORS RESEARCH CORPORATION, OF DAYTON, OHIO, A CORPORATION
OF DELAWARE.

ENGINE CONSTRUCTION.

Application filed June 21, 1919. Serial No. 305,782.

To all whom it may concern:

Be it known that I, CHARLES F. KETTERING, a citizen of the United States of America, residing at Dayton, county of Montgomery, State of Ohio, have invented certain new and useful Improvements in Engine Constructions, of which the following is a full, clear, and exact description.

This invention relates to engines, and 10 more particularly to the cooling of engines especially of the so-called, air-cooled type.

One of the principal objects of this invention is to provide an engine construction adapted to the proper cooling of the engine, 15 and especially of the engine cylinders.

Other objects and advantages will be apparent from the description set out below, when taken in connection with the drawings.

In the drawings:
20 Fig. 1 is a view, partly in section, of an engine embodying my improved construction, including what I term an equalizer, and adapted for up-draft cooling;

Fig. 1^a is a fragmentary view of Fig. 1
25 showing the equalizer and an insulator;

Fig. 2 is a view, similar to Fig. 1, in
which the engine is adapted for down-draft
cooling;

Fig. 3 is a fragmentary view of a cylinder
30 having a modified form of such equalizer;

Fig. 4 is a detail view of the equalizer
shown in Fig. 3;

Fig. 5 is still another modified form of
cylinder construction; and

35 Fig. 6 is a fragmentary view showing a
form of finning.

This invention, for purposes of easier description, will be described in connection with an air-cooled internal-combustion engine. It must be borne in mind, however, 40 that the invention is not limited to the specific type of engine disclosed.

In the cooling of the conventional air-cooled internal-combustion engine one of 45 the primary problems which must be solved is the removal of heat from the engine cylinders to secure satisfactory working conditions. The cylinders of an internal-combustion engine consist broadly of a barrel portion and a head portion. The cooling of 50 the cylinder barrel may be a comparatively simple matter, but the cooling of the cylinder head is much more difficult. The flow of cool incoming gases through the inlet port

and of very hot outgoing gases through the 55 exhaust port tends to cause irregular heat distribution through the cylinder head, with consequent distortion due to irregular expansion. Appreciating the importance of this situation, and in order to secure satisfactory operating conditions, I aim to control the temperature of the cylinder head so as to maintain a uniform heat distribution thereover and to keep the peak temperature below a definite maximum. The superstructure—and by superstructure I mean the valve mechanism, the inlet and exhaust pipes, the spark plugs, etc.—renders proper temperature control of the cylinder head extremely difficult. 70

In Fig. 1 is illustrated a type of air-cooled engine in which the cylinder is so constructed as to secure proper cooling of both the cylinder barrel and the cylinder head. The engine shown in Fig. 1 comprises a crank 75 case 10 and a fly wheel 11. Mounted upon the crank case is a cylinder 20, which may be of steel, cast iron or other suitable material. As shown this cylinder comprises a barrel portion 21 and a head portion 22. 80 Carried by the head portion are the inlet and exhaust conduits 23, 24, which are controlled by the valves 25 and 26. Also carried by the head portion are the rocker arms 27, adapted for actuating the valves. These elements 85 constitute what I call, the "superstructure." Attached to the cylinder barrel is a plurality of radiating elements or cooling fins 30. These fins should be of some material which is a good conductor of heat, and I preferably use copper, which has given very satisfactory results. By using a fin material which is such a good conductor of heat as copper the thickness of the fins may be materially decreased, and a greater number of 90 fins thus secured, with a consequent increase in radiating surface, without loss in the conductive capacity of the fins or in the capacity of the air passages between the fins. The fins are preferably formed from a single 100 sheet of metal corrugated, or plaited, as shown in Fig. 6. The form of fin shown is, of course, merely one form that may be used and any other type adapted to give a corresponding radiating surface and conductivity 105 might be used just as well. In attaching the fins to the cylinder barrel the aim should be to provide an effective thermal contact. It

is not sufficient that the fins and the cylinder barrel be in ordinary metal-to-metal contact, but their relation should be such that there will be little resistance to the flow of heat 5 from the cylinder into the fins. This desired condition I have, for convenience, termed "effective thermal contact." One manner of securing this effective thermal contact of the two materials is to weld or 10 solder the fins to the cylinder, using any suitable solder, such, for example, as conventional silver, or lead-tin, solder. Other methods of securing such thermal contact may be utilized and in copending applications 15 are described further ways of accomplishing this result.

Attached to the head portion of the cylinder is what, for convenience, I have termed an equalizer 35. The equalizer 20 shown in Fig. 1 and Fig. 1^a consists of a cup-shaped member adapted to contact with the cylinder head, and the upper end of the cylinder barrel. This equalizer is composed of a material which is a good conductor 25 of heat, preferably copper, and the object thereof is to equalize the heat in the cylinder head so as to give a uniform distribution of heat therein. By using an equalizer which is a good conductor of heat, 30 and extending the equalizer outwardly beyond the cylinder wall it is possible to secure both a uniform distribution of heat over the cylinder head and a cooling of that cylinder head to thus lower the maximum 35 peak temperature attained thereby. As shown in Fig. 1 the equalizer does not extend straight out but its outer edge is brought down into contact with the upper end of the cylinder barrel, the fins 30, at 40 their upper ends being attached to the down-turned portions of the equalizer. By this construction the heat carried off from the cylinder head by the equalizer is transferred to the fins 30 whence it is taken up by the 45 cooling air, and a very substantial cooling of the cylinder head thus secured. In attaching the equalizer to the cylinder head and the upper part of the cylinder barrel, the same effective thermal contact should 50 preferably be secured as is above described as being secured between the fins and the cylinder barrel. Where a cast iron cylinder is used a very satisfactory manner of 55 attaching the equalizer to the cylinder head is to use silver solder. This method of attachment also applies in the case of a steel cylinder. Where a steel cylinder is used the equalizer may also be attached by casting the copper upon the cylinder. Other ways 60 of attaching the equalizer to the head portion of the cylinder may be used, several such ways being disclosed in copending applications. The upper ends of the fins 30 should be in thermal contact with the copper 65 equalizer.

Interposed between the equalizer 35 and the superstructure is a layer of insulating material, 40, such as asbestos, mica, or analogous material. As shown this insulating material is interposed between the equalizer 70 and the entire superstructure. It is not essential, however, that the precise type of insulator disclosed be used, as other means of insulating the superstructure from the cylinder head and equalizer might function 75 just as satisfactorily. The function of this insulator is to prevent the back flow of heat from the superstructure to the equalizer and cylinder head. Generally it is not necessary that the entire superstructure be insulated 80 from the equalizer and cylinder head, though it is usually simpler in actual practice to so arrange the insulating material. It is very important, however, that the exhaust conduit be insulated. To assist in 85 dissipating the heat within the walls of the exhaust conduit the cooling elements or fins 41 are arranged thereon.

Surrounding the cylinder and the fins carried thereby is a draft tube 45, the lower 90 end of which is seated upon, and opens into, the crank case. Upon the operation of the engine there is a flow of cooling air through the draft tube, bringing a large quantity of air into contact with the cooling elements of the cylinder. For causing the desired flow of cooling air through the draft tube and over the cooling elements of the cylinder I preferably make use of a positive, or pressure, blower 50, having a delivery 100 pipe 51, opening into the draft tube below the lower ends of the fins. This blower may be any of the approved or well known types, and, as illustrated, it is driven directly from the crank shaft of the engine, 105 as by means of gears. In Fig. 1, a gear 52 is shown, carried by the crank shaft, which meshes with another gear, not shown, mounted upon the shaft 53 of the rotor element of the blower. By properly proportioning 110 the gears the blower may be operated at the speed necessary for delivering the desired quantity of cooling air through the draft tube. If desired other means for driving the blower may be used, for example, it 115 may be driven from the fly wheel by means of a belt.

A cylinder of the type described is not limited in its applicability to an engine furnishing up-draft cooling air but it will 120 also operate satisfactorily with a down-draft. In Fig. 2 is shown an engine embodying my improved cylinder construction in which the flow of cooling air is furnished by a suction fan 60 incorporated in the fly 125 wheel. The structure shown in Fig. 2 is identical with that shown in Fig. 1, with the exception of the mechanism for causing a flow of cooling air. With the exception of the cylinder structure the device shown 130

in Fig. 2 is similar to the engine structure illustrated and described in copending application No. 58,207, filed October 27, 1915.

Figs. 3 and 4 show a modified form of cylinder construction in which the equalizer is in the form of an up-turned cup 35^a. This cup is attached to the cylinder head 22, in the same manner as described in connection with the cup shown in Fig. 1. In making up a cup such as shown in Figs. 3 and 4 a disc of copper of the desired diameter and thickness, the dimensions of the disc being dependent upon the cylinder dimensions, is slit along its outer edge, the depth of the slits being such as to leave the central, or non-slit, part 66 of the disc of substantially the same diameter as the cylinder head, and alternate slit portions 67 are then up-turned, as clearly shown in Fig. 4. This provides an equalizer in which every other slit portion is up-turned to provide, roughly, a cup, the slit portions not up-turned projecting outwardly beyond the cylinder. These slit portions when in this form provide a species of fins or radiating elements by means of which the heat distributed through the equalizer is more effectively transferred into the cooling air. The up-turned slit portions are so positioned that a place is provided for the inlet conduit and the exhaust conduit. Interposed between the upper surface of the equalizer cup and the lower surface of the cylinder superstructure is a layer of insulating material 40, which insulating material, as described in connection with Fig. 1, may be of asbestos, mica, or other analogous material. The valve mechanism, the fins, etc., shown in this modified form of apparatus are substantially identical with the corresponding parts shown in Fig. 1.

In Fig. 5 is shown still another modified form of cylinder construction in which the equalizer 35^b is in the form of a plate or disc, instead of a cup as shown in Figs. 1, 2, 3 and 4. This equalizer is also of copper, or some other material which is a good conductor of heat. In this modified form of cylinder the fins, at their upper ends, contact with the equalizer plate. The draft tube 45^b and outer faces of the fins 30^b, however, are cut away a short distance below the equalizer to permit of the passage of cooling air. In this modification, as in those described above, a heat insulating member 40 is inserted between the upper surface of the equalizer plate and the lower surface of the superstructure.

In Fig. 6 is shown a fragmentary sectional view through the cylinder shown in Fig. 1, along the line 6—6. As shown in this figure the cooling fins, which are attached to the equalizer and to the cylinder, are made from a continuous strip of material which is bent upon itself, somewhat in

the form of accordion plaiting, each fold constituting a fin of the desired dimensions. The same type of fin is used in the modifications shown in Figs. 2, 4 and 5. Obviously the fins need not, of necessity, be made of copper inasmuch as any other material of sufficiently good conductivity might be substituted therefor. And they need not be made from a continuous strip, separately formed fins being very satisfactory. Also two sets of fins may be used on each cylinder, one set for the equalizer and another set for the cylinder barrel, the fins being so attached that the air passages between them are not obstructed. The fins, however, regardless of their form or the material constituting them, should preferably be in substantially true thermal contact with the cylinder.

While I have illustrated cylinders having vertical, or longitudinal, fins my invention is not limited to that particular structure, as I may also use circumferential fins. In such case the equalizer would be similar to that shown in Fig. 5, and would also function as a fin. This type of construction is peculiarly adaptable to airplane engines in which large quantities of air move over the cylinders as a result of the propeller action and the movement of the airplane through the air.

All of the cylinders described are adapted to function in the same general manner. The equalizer, regardless of its form, is composed of a material which is a good conductor of heat and is adapted to maintain substantially uniform the heat distribution throughout the cylinder head. And the fins should be of a material having the same characteristic. Also both the equalizer and fins preferably be in effective thermal contact with the cylinder head. The equalizer need not be of different material, or a separate member, from the cylinder head, as substantially the same result could be secured with an equalizer which is integral with, and of the same material as, the head. But it is extremely important that the cylinder head be so constructed as to secure a uniform heat distribution thereover, and to provide some means for radiating a part of this heat into the cooling air.

While the insulator between the cylinder head, or equalizer, and the superstructure is not an absolute necessity, under all normal conditions it tends to secure more satisfactory operation of the engine. By preventing the back flow of heat from the exhaust conduit to the cylinder head and equalizer it permits of more uniform heat distribution through the equalizer and head and of more ready cooling of the head.

While the forms of mechanism herein shown and described constitute preferred forms of embodiments of the invention, it

is to be understood that other forms might be adopted, all coming within the scope of the claims which follow.

What I claim is as follows:

- 5 1. In an engine; a cylinder comprising a barrel portion and a head portion; a superstructure carried by said head portion; and insulating material between the head portion and the superstructure.
- 10 2. In an engine; a cylinder comprising a barrel portion and a head portion; an equalizer attached to the head portion; a superstructure carried by said head portion; and means for insulating the head portion from the superstructure to obstruct the transfer of heat therebetween.
- 15 3. In an engine, a cylinder comprising a barrel portion and a head portion; an equalizer attached to the head and in effective thermal contact therewith; a superstructure carried by the head; and heat insulating material between the equalizer and the superstructure.
- 20 4. An engine cylinder comprising a barrel portion and a head portion; a copper equalizer attached to the head portion; a superstructure carried by the head portion; and heat insulating means between the equalizer and the superstructure.
- 25 5. An engine cylinder comprising a barrel portion and a head portion; an equalizer attached to the head portion, said equalizer being composed of a material which is a good conductor of heat, and extending outwardly beyond the cylinder to permit of more ready cooling thereof; a superstructure carried by the head; and heat insulating means between the equalizer and superstructure.
- 30 6. An engine cylinder comprising a barrel portion and a head portion; an equalizer attached to the head portion, said equalizer being composed of a material which is a good conductor of heat; cooling elements associated with the equalizer; a superstructure carried by the head portion; and means interposed between the superstructure and the equalizer for preventing the ready transfer of heat therebetween.
- 35 7. An engine cylinder comprising a barrel portion and a head portion; an equalizer attached to the head portion, said equalizer being cup-shaped to offer little obstruction to flow of cooling fluid over the cylinder; a superstructure carried by the head portion; 55 heat insulating means between the equalizer and the superstructure and means for causing flow of cooling fluid over the cylinder.
- 40 8. An engine cylinder comprising a head portion and a barrel portion; a cup-shaped equalizer attached to the head portion; cooling elements associated with the equalizer; a superstructure carried by the head portion; and means for preventing the ready transfer of heat between the equalizer and superstructure.
- 45 9. An engine cylinder comprising a barrel portion; a head portion; an exhaust conduit carried by the head portion; and heat insulating means for preventing the ready transfer of heat between the head portion and exhaust conduit.
- 50 10. An engine cylinder comprising, a barrel portion; a head portion; an exhaust conduit carried by the head portion; and 75 an insulator of asbestos between the head portion and exhaust conduit to prevent the ready transfer of heat therebetween.
- 55 11. In an air cooled engine, a cylinder comprising a barrel portion; a head portion 80 having an equalizer, composed of a material which is a good conductor of heat, attached thereto; a superstructure carried by the head portion; heat insulating means between the equalizer and the superstructure; and means 85 for causing a flow of cooling air along the cylinder toward the head portion thereof.
- 60 12. In an air cooled engine, a cylinder comprising a barrel portion; a head portion having an equalizer, composed of a material 90 which is a good conductor of heat, attached thereto; a superstructure carried by the head portion; heat insulating means interposed between the equalizer and superstructure; cooling fins attached to the equalizer and 95 barrel portion of the cylinder; a draft tube surrounding said fins; and means for causing a flow of cooling air through said draft tube toward the head portion of the cylinder.

In testimony whereof I affix my signature. 100
CHARLES F. KETTERING.
